VALVE CONSTRUCTION

Ivar L. Langvand, Barberton, Ohio, assignor to
 The Babcock & Wilcox Company, New York,
 N. Y., a corporation of New Jersey

Application February 7, 1948, Serial No. 6,907

8 Claims. (CL. 277-19)

1

This invention involves an improvement in a valve construction, and more particularly in a valve particularly adapted for use as an attemperator control valve, automatically operable in response to temperature changes of a high temperature fluid, to variably proportion the fluid flow between two flow paths one of which bypasses an attemperator while the other includes the attemperator. Such a valve is particularly adapted in a system for controlling the superheat in a high pressure steam generator-superheater installation.

In casting a metal body for a high pressure valve adapted for use with superheated steam of a pressure of the order of 1200 p. s. i. and above, the external walls must be of substantial thickness while the diaphragm, because of the limited difference in pressures on its opposite sides may be made relatively thin to advantageously attain a compact structure.

It is an object of the present invention to provide a valve construction for such purposes having a thick wall valve body with an integral diaphragm which is so arranged that any stresses which may occur during changing temperature conditions involved in the casting of the valve body and diaphragm, or which may occur under high pressure and temperature operating conditions may be controlled and limited in their final effect on the diaphragm, in such a manner that the operation of the valve will not be functionally impaired.

More specifically it is the object of the invention to provide an integral diaphragm extending between opposite thick walls of a valve body which is so arranged that the strains, resulting from the cooling of the molten cast metal of the diaphragm or as the result of operating temperature conditions, will occur within the diaphragm. To this end, the transverse diaphragm which is cast integrally with the opposite body walls is arranged with a central elongated wall section of materially less thickness than the remainder of the diaphragm to provide a zone for localization of such strains. Such a strain may be evidenced by a crack, but because of its symmetrical location with respect to the contiguous opposite walls and because of its limited character will not involve an opening of sufficient flow area to impair the functioning of the diaphragm as a means for separating the flow passages.

The invention will be described with reference to the accompanying drawing in which a preferred embodiment is shown, and other objects

2

of the invention will appear as the description proceeds.

In the drawings:

Fig. 1 is a longitudinal section through the illustrative valve;

Fig. 2 is a longitudinal section at right angles to Fig. 1, taken on the line 2-2 of Fig. 1, and looking in the direction of the arrows applied to that section line;

Fig. 3 is a transverse section on the line 3-3 of Fig. 1, and looking in the direction of the arrows; and

Fig. 4 is a fragmentary section on the line 4-4 of Fig. 2, illustrating the diaphragm construction in the zone of its weakened section extending along a median line aligned with the axis of the valve damper.

The illustrative valve includes a valve body 10. This is a single piece casting forming an inlet 12, the main outlet 14, and a side outlet 16. Formed as an integral part of the casting and dividing the flow paths leading to the separate outlets is a transverse diaphragm 18, the upstream edge of which is disposed closely adjacent to the circumferential edge of the circular central web 20 of a two-bladed damper 22. This damper is a single piece casting with the valve blades 24 and 26, on opposite sides of the web 20, set 90° apart as clearly indicated in the drawings (Fig. 2). The web 20 forms a substantial continuation of the flow dividing wall formed by the diaphragm 18, and, due to the 90° setting of the valve blades, the flow to the outlet 14 is decreased and the flow to the outlet 16 simultaneously and correspondingly increased when the damper is turned in one direction.

Due to the fact that the diaphragm 18 is integral with the valve body casting, and also due to the wide temperature differentials to which the valve parts are subjected when the valve is used as a part of a system for controlling the superheat of high temperature steam, thermally created stresses of considerable magnitude may develop in the diaphragm. They are apt to result in such cracking of the diaphragm that the effectiveness of the valve might be impaired. This is prevented and the position of cracking controlled by constructing the integral diaphragm of relatively small wall thickness and of spherical surface with a linear (or circumferential) section of reduced thickness, as indicated at 30 in the drawings. This section extends intermediate of the diaphragm, from a point midway of the curved free edge of the diaphragm adjacent to the web 20 to a point midway of the opposite side

of the diaphragm where it joins the thicker metal of the valve body adjacent the side outlet 16. With this construction, if the diaphragm is caused to crack by thermally created stresses, the crack will occur along the line of the reduced section 30, and the sections on either side of the crack will not be subject to unequal stress conditions because of the location of the crack in its central position.

The diaphragm 18 is of a spherical form having its upper circular free edge 19 in alignment with the circular valve web 20, while the other margins are integrated with the body walls. The spherical form contributes to its strength as a diaphragm and avoids straight line strut or tie action between the spaced side walls of the valve body. As shown by Figs. 1 and 4 the diaphragm has a circumferential section 30 of reduced thickness extending from the free edge 19 to the lower edge 21 where the diaphragm joins the body at the bottom of the outlet portion 16. In the illustrative valve where the connections 12, 14 and 16 are of 7 $\frac{1}{4}$ " internal diameter and the body wall thickness of the order of 2 inches, the diaphragm is of spherical form having a radius of 14 inches, and of a wall thickness of $\frac{5}{8}$ inch tapering down to a minimum wall thickness of $\frac{1}{4}$ inch as shown by Fig. 4. The wall thickness reduction is accomplished by grooves from both faces of the diaphragm so that the remaining wall thickness is symmetrically positioned between the contiguous main portions of the diaphragm. A small hole 23 of a diameter of the order of the minimum wall thickness extends through the diaphragm at its lower margin for the purpose of preventing the extension of any strain effect beyond the margin of the diaphragm and into the body wall.

With the above described arrangement, the spherical shaped diaphragm is so supported from the surrounding body that even should a crack develop along the predetermined line of the reduced thickness no appreciable relative displacement of the edges marginal to the crack will occur and substantial leakage through the diaphragm will be avoided.

The valve damper 22 is rotatably mounted at its right-hand side (Fig. 1) within a bonnet 32 removably secured over a side opening in the valve body by the bonnet studs 34 and their associated stud spools 36 and hex-nuts 38.

The bonnet 32 has a finned extension 40 within which is rotatably mounted a valve stem 42, with the interposed thrust bushing 44, thrust collar 46, packing 48, stuffing box gland 50 tightenable by a stud 51, and outer bushing 52. The outer end of the valve stem is squared as at 54 for the reception of a valve operating member, and provided with a washer 56 and a top bolt 58 for holding an operating member on the valve stem. The opposite end 60 of the valve stem, on the opposite side of the thrust collar 62, is similarly squared and operatively joined by the sleeve 64 with the similarly squared stud 66 integral with the damper 22. A pin 68 secures the sleeve 64 to this stud. To the left of sleeve 64 the damper is formed with a bearing stud 70 rotatable within the top damper bushing 72.

The rotatable mounting at the opposite side of the damper includes the bearing stud 74, the lower damper bushing 76, and the end plug 78 secured to the valve body 10 by the end plug studs 80.

What is claimed is:

1. In a valve, a one piece metallic valve body

presenting separate valve outlets and a transverse diaphragm separating flow paths extending from the valve interior to said outlets, said diaphragm having a line section of reduced wall thickness at an intermediate position relative to the diaphragm width, the wall thickness of said line section of the diaphragm being much less than the wall thickness of the remainder of the diaphragm to present a thermal stress localizing line across the diaphragm.

2. In a valve construction, an integral metallic valve body presenting two separate valve outlets, and means mounted in said body for movement to control fluid flow through said outlets, said body having a diaphragm separation fluid flow paths from said means to said outlets and having a free edge adjacent said means and extending across the valve body at a position remote from said outlets, said diaphragm also having a line section of reduced wall thickness extending across the diaphragm to an intermediate position along the free edge of the diaphragm, the wall thickness of said line section of the diaphragm being much less than the wall thickness of the remainder of the diaphragm to present a thermal stress localizing line across the diaphragm.

3. In a valve for variably proportioning fluid flow through a plurality of valve outlets, an integral metallic casting presenting said outlets and an inlet, and means turnably mounted and extending across the interior of the valve body for regulating the flow of fluid to said outlets, said valve body casting having an integral diaphragm extending across the interior of the valve body and dividing flow paths leading from said means to said outlets, the diaphragm having a free edge adjacent said means and extending across the casting at a position remote from said outlets, said diaphragm being grooved to present a narrow stress localizing zone along a median line section of a wall thickness substantially less than the thickness of the remainder of the diaphragm, said section extending from a position along the inner surface of said body and between said outlets to an intermediate position along the free edge of the diaphragm and adjacent said means.

4. In a branched valve construction, a single piece metallic tubular valve body presenting a main fluid flow path and a branch communicating therewith, a diaphragm integral with said body and disposed transversely of the valve body and providing a continuation of the branch into the valve body, and flow control means mounted within the valve body and extending transversely of the branch and the main fluid flow path, said means including oppositely effective valve damper elements at different radial positions and operable across the branch and the main fluid flow path on opposite sides of the diaphragm, one of said valve members closing the branch while the other valve member is opening the main fluid flow paths, said diaphragm being grooved to present a narrow zone of localization of thermal stresses along a line section extending in the general direction of fluid flow from an intermediate position adjacent the flow control means to a position intermediate the outlets for said branch and the main flow path, the wall thickness of said line section of the diaphragm being much less than the wall thickness of the remainder of the diaphragm to present a thermal stress localizing line across the diaphragm.

5. In a valve, a one piece metallic valve body presenting separate valve outlets and a transverse diaphragm separating flow paths extend-

ing from the valve interior to said outlets, said diaphragm having a line section of reduced wall thickness at an intermediate position relative to the diaphragm width and extending generally in the direction of fluid flow, the wall thickness of said line section of the diaphragm being much less than the wall thickness of the remainder of the diaphragm to present a thermal stress localizing line across the diaphragm.

6. In a valve construction, an integral metallic valve body presenting two separate valve outlets, and means mounted in said body for movement to control fluid flow through said outlets, said body having a diaphragm separating fluid flow paths from said means to said outlets and having a free edge adjacent said means and extending across the valve body at a position remote from said outlets, said diaphragm having a line section of reduced wall thickness extending transversely of the free edge of the diaphragm to an intermediate position along the free edge of the diaphragm, the wall thickness of said line section of the diaphragm being much less than the wall thickness of the remainder of the diaphragm to present a thermal stress localizing line across the diaphragm.

7. A unitary metallic valve body presenting a single fluid inlet and a plurality of fluid outlets, and means movably mounted within the body for controllably dividing the fluid flow from said inlet into a plurality of paths leading to the outlets, said body having a transverse diaphragm separating said paths extending from said means to the outlets, the diaphragm being grooved along a line extending from a position adjacent said

means and intermediate the width of the diaphragm to a position adjacent said outlets and also intermediate the diaphragm width to present a narrow zone of localization of thermal stresses.

5 8. A one piece metallic valve body presenting a single fluid inlet and a plurality of fluid outlets, and means movably mounted within the body for controllably dividing the fluid flow from said inlet into a plurality of paths leading to the outlets, said body having an integral transverse diaphragm separating said paths extending from said means to the outlets, the diaphragm being grooved on both sides along a line extending from a position adjacent said means and intermediate the width of the diaphragm to a position adjacent said outlets and also intermediate the diaphragm width to present a narrow zone for the localization of thermal stresses.
